CLAMP FOR CONCRETE FORMS
 Frederick R. Langford, 1313 Luneta Drive,
 Del Mar, Calif.
 Filed July 20, 1964, Ser. No. 383,853
 5 Claims. (Cl. 249—192)

The present invention relates to a forming system comprising a plurality of adjacent panels whose edges are contiguous. The panels are interconnected by a device which permits the adjustment of the relative position of adjacent panels. This adjusting device provides for the forming of a surface which is even and which is free from misaligned surface treatments such as grooves produced by inserts between panels. In other respects the forming system is similar to conventional panel forming of concrete.

The invention utilizes sealing means between the panels to prohibit the egress of the formed substance. This feature is very beneficial in the case where the formed substance is concrete. When water leaks from formed concrete, the hardened concrete, in the vicinity of a leak, has a rough uncemented sandy finish. Since the sealing means prohibits leakage, a concrete surface formed with the system of the present invention is without such uncemented sandy finish defects.

Other features and the advantages of the present invention will be apparent from the following description, reference being made to the accompanying drawings wherein a preferred embodiment of the invention is illustrated.

In the drawings:

FIG. 1 is a plan view of the form clamp;
 FIG. 2 is a front view of the form clamp;
 FIG. 3 is a side view of the sealing means;

FIG. 4 is a plan view of the sealing means taken along line 4—4 of FIG. 3, the elastic element being shown expanded;

FIG. 5 is a fragmentary back view of the sealing means taken along line 5—5 of FIG. 3;

FIG. 6 is a cross-sectional view of the forming panels and of the sealing means with the elastic element uncompressed, the form clamp being shown beyond; and

FIG. 7 is a cross-sectional view of the form clamp and sealing means taken along line 7—7 of FIG. 6.

Referring in detail to the drawings, FIG. 7 illustrates the forming system, the principal elements of which are the panels 20 and 22, the form clamp 24 and the sealing member 92 or 94.

The clamp 24 includes an angle 26 with one leg 28 extending vertically and one leg 30 extending rearwardly, angles 32 and 34, one of which is located at each end of angle 26, and which extend forwardly of angle 26 and at right angles to leg 28, and upright sections 36 and 38 which extend forwardly of angle 26 and at right angles to leg 28. Angles 32 and 34 have upright legs 40 and outwardly facing legs 42. The ends of legs 42 are each flush with an end of angle 26. Upright sections 36 and 38 are in proximity to center of angle 26 and are joined at their forward ends by upright section 44. The upright legs 40 and the upright sections 36 and 38 are equally spaced along leg 28. This spacing produces two channels 46 and 48 with the open ends on the forward side of clamp 24, and a hole 50 defined by members 28, 36, 38 and 44.

Holes 52, 54, 56, 58, 59, 60, 62, 64 and 66 are provided to receive nails 68, 70, 72, 74, 75, 76, 78, 80 and 82, respectively. Holes 52 and 66 are in legs 40 and are located adjacent legs 42. Holes 56 and 62 are in leg 28 and are located adjacent leg 30 and proximately in the center of channels 46 and 48, respectively. Holes 54, 58

2

are so located that their forward projection forms forward extending channels 84 in legs 40 and sections 36 and 38, as shown in the sectional portion of FIG. 1. Channels 84 are in the forward extending sides of channels 46 and 48. Hole 59 extends downwardly and forwardly through leg 30.

Panels 20 and 22 include upward extending edge flanges 85 and 86, respectively, and vertical forming panels 88. The flanges are affixed to the forming panels.

10 The vertical extending sealing members 92 and 94 each includes a main body 96, an elastic seal 98, a forward extending tongue 100 and separator nails 102. The sealing members being symmetric in cross section with respect to its forward and rearwardly extending axes.

15 The main body 96 is made of one piece of metal which forms a channel shape which closes on itself at the forward extending end 104. The main body 96 is uniform in shape with respect to its vertical length, has a constant depth, but has four different widths. The rear portion 20 106 of the main body 96 has a width substantially equal to and a depth less than that of hole 50 of form clamp 24. The back wall 108 of the rear portion 106 confronts leg 28 of form clamp 24 where the rear portion 106 passes through said clamp. The side walls 110 of the 25 rear portion 106, confront upright sections 36 and 38 of the form clamp 24 where the rear portion 106 passes through said clamp.

20 A spacer portion 112 of the main body 96, which has parallel walls 114 whose interior sides are spaced by a distance substantially equal to the width of a separator nail 102, lies adjacent and forwardly of rear portion 106.

Fins 116, extend laterally adjacent and forwardly of spacer portion 112, one extending from each side.

25 Forward extending and confronting separator walls 35 118, which abut one another and form the open end 104 of the main body 96, lie adjacent and forwardly of the fins 116.

The rear wall 108 of the main body 96 has holes 120 for the insertion of separator nails 102. The separator

40 nails 102 (see FIG. 4) are inserted in holes 120, extended through the rear wall 108, and the spacer portion 112, and are forced between separator walls 118. The forcing of the separator nails 102 between separator walls 118 causes the walls to move laterally. The shank length of the separator nails 102 having a length substantially equal to the depth of the main body 96.

45 The elastic seal 98 has a T-shaped cross section with a forward extending leg 122 and laterally extending arms 124, each arm encompassing one of the laterally extending fins 116. The forward extending leg 122 encompasses the separator walls 118 and has a width that is substantially equal to the space between the panels 20 and 22. When the separator walls 118 are moved laterally, the forward extending leg 122 is stretched laterally.

50 55 The tongue 100 lies forwardly of leg 122 and protrudes into the formed substance. The shape of this tongue may be chosen to give the desired surface design.

The lower portion of the spacer portion 112 of the 60 main body of each of the sealing members was removed to provide a slot 130 for the upright portion 44 of clamp 24, to allow the lower end of the upper sealing member 92 to pass through the clamp 24.

The forming system is erected in the following manner: One of the panels 20, for example panel 20 is already in place, and the remaining panel 22 is placed contiguous to panel 20. The channels 46 and 48 of the form clamp 24 are placed, respectively, over the flanges 85 and 86 which respectively protrude from the non-forming surfaces of panels 20 and 22. Each of the channels 46 and 48 is wider than either of the wood flanges 85 and 86. Holding nail 72 is then driven through hole

56 so as to seat the back side of channel 46 against the back side of flange 85. Holding nail 68 is then driven through hole 52 to prevent nail 72 from pulling out. Wedging nails 70 and 74 are then driven through holes 54 and 58, respectively. The wedging nails 70 and 74 are guided by grooves, one of which is shown at 84. The depth of the grooves is less than the diameter of the wedging nails. The wedging nails in combination with channel 46, fit snugly against the sides of flange 85. At this point in the erection sequence the form clamp 24 is 10 firmly affixed to panel 20.

The next step in the erection sequence is to position panel 22 such that edges 126 and 128 of panels are parallel and are spaced such that the leg 122 fits snugly in the space between edges 126 and 128. Only a small 15 adjustment is necessary to accomplish this result since the channels 46 and 48 and the flanges 85 and 86 are constructed so that the panels 20 and 22, in combination with the form clamp 24, are substantially aligned before the nails are driven through the form clamp. After panel 22 is properly positioned, holding nail 78 is driven in hole 62, then wedging nails 76 and 80 are driven in holes 60 and 64, respectively. Holding nail 82 is driven in hole 66 to prevent the flange 86 from being pulled out of channel 48. At this point the panels 20 and 22 are firmly held 25 together and positioned by the form clamp and its associated nails.

As previously mentioned holes 52 and 66, and 56 and 62 are adjacent surfaces 42 and 30, respectively. Therefore nails 68, 72, 78 or 82 can only be driven until their 30 heads abut the outer edges of said surfaces. This feature permits the easy removal of the nails.

If panels 20 and 22 are made of the same size material, the outer corner of edges 60 and 62 will be parallel.

With the panels 20 and 22 in position, sealing member 94 is placed so that leg 122 fits between confronting edges 126 and 128 of adjacent panels. The top end of sealing member 94 is placed just below the bottom of the form clamp 24. Sealing member 92 is then placed by inserting 40 the main body 96 through hole 50 of form clamp 24. The bottom end of the main body 96 abuts the upper end 132 of sealing member 94. Tab 134 is attached to the back surface 108 of tongue 130 and extends over the back surface 108 of member 94.

Nail 75 is then inserted in hole 59 and is driven in wedging relationship with tab 134. This wedging action forces the elastic leg 122 of elastic seal 98, into the space between edges 126 and 128, and forces the arm 124 of said seal against the back sides of panels 20 and 22 so as to effectuate a seal between said arms and sides.

The separator nails 102 are then driven so as to laterally expand leg 122 of seal 98, thus effectuating a seal between edges 126 and 128. As many separator nails as required to effectuate the seal would be driven.

While the form of embodiment herein shown and described constitutes a preferred form, it is understood that other forms may be adopted falling within the scope of the claims that follow.

I claim:

1. A forming system comprising in combination:

(A) A plurality of panels whose edges are substantially contiguous and which in combination form a continuous forming surface;

(1) said panels each have at least one flange protruding from the non-forming surface, said flange being adjacent a panel edge;

(B) means cooperating with adjacent flanges of adjacent panels for holding the panels in contiguous relation;

60

65

70

70

- (C) a sealing member disposed between confronting edges of the panels;
- (D) and wedging means for spreading the sealing member into sealing relationship with the confronting edges of the panels.

2. A forming system comprising in combination:

(A) A plurality of panels whose edges are substantially contiguous and which in combination form a continuous forming surface;

(1) said panels each have at least one flange protruding from the non-forming surface, said flange being adjacent a panel edge;

(B) means cooperating with adjacent flanges of adjacent panels for holding the panels in contiguous relation and for adjusting the space between panel edges, said means comprised of:

(1) channels spaced so as to receive said flanges, the respective widths of said channels being greater than the respective flange widths;

(2) wedging means having a first portion between the channels and having a second portion extending between the edges of the panels;

(3) interconnecting means for spacing and interconnecting said channels;

(4) fastening means for fastening the channels to the flanges.

3. A forming system comprising in combination:

(A) A plurality of panels whose edges are substantially contiguous and which in combination form a continuous forming surface;

(1) said panels each have at least one flange protruding from the non-forming surface, said flange being adjacent a panel edge;

(B) means cooperating with adjacent flanges of adjacent panels for holding the panels in contiguous relation and for adjusting the space between panel edges;

(C) sealing means between and adjacent to at least one of the pairs of contiguous edges, said sealing means comprising:

(1) a continuous member located on the non-forming side of the panels and adjacent the space between the contiguous edges;

(2) a continuous elastic member attached to said continuous member and positioned in said space and adjacent the non-forming side of said panels;

(3) means for compressing said elastic member against the non-forming side of said panels;

(4) means for expanding the elastic member to substantially fill said space.

4. A forming system as defined in claim 1, characterized in that the sealing member is formed of elastic material.

5. A forming system as defined in claim 1, characterized in that the wedging means includes:

(1) confronting legs, movable away from one another;

(2) and a wedge movable between said confronting legs.
